UNITED STATES PATENT OFFICE.

JOSEPH J. NEEDLE, OF COLLINSVILLE, ILLINOIS.

WINDOW-LOCK.

1,358,867.

Specification of Letters Patent. Patented Nov. 16, 1920.

Application filed April 9, 1917. Serial No. 160,649.

To all whom it may concern:

Be it known that I, JOSEPH J. NEEDLE, a citizen of the United States of America, and a resident of Collinsville, in the county of Madison and State of Illinois, have invented certain new and useful Improvements in Window-Locks, of which the following is a specification.

The primary object of this invention is to provide an improved locking mechanism for windows, in which the releasing mechanism is located at a distance away from the window so that if an intruder broke a portion of a window pane for the introduction of his hand, he cannot reach the releasing mechanism.

Another object is to provide an improved locking mechanism that will automatically lock the sashes when they are moved to a closed position.

Other and further objects will appear in the specification and be specifically pointed out in the appended claims, reference being had to the accompanying drawings exemplifying the invention, and in which,

Figure 1 is a fragmentary portion of a wall of a room showing a window and this improved locking device applied thereto.

Fig. 2 is an enlarged fragmentary horizontal section taken on the line II—II of Fig. 1.

Fig. 3 is an enlarged fragmentary vertical section taken on the line III—III of Fig. 2.

Fig. 4 is an enlarged fragmentary vertical section taken on the line IV—IV of Fig. 2.

Fig. 5 is a transverse section of a portion of a window sash showing how a metallic channel member can be applied thereto to serve as a wearing surface to the locking bolts.

Fig. 6 is a view showing how this improved locking device can be manipulated relative to a pair of windows.

Referring to the drawings, 1 designates the wall of a room, 2 a window frame, 3 the upper sash and 4 the lower sash. Reciprocally mounted in bushings 5 and 6, which are located in one side of the window frame 2, are a pair of locking bolts 7 and 8, respectively, said locking bolt 7 being adapted to engage a socket or pocket 9 which is formed in the upper sash 3, whereas the bolt 8 is adapted to engage a socket 10 which is formed in the lower sash 4.

Secured on the inside of the wall 1 is a guiding bracket 11, said locking bolts 7 and

8 being reciprocally mounted in said bracket. Formed on one end of each of the bolts 7 and 8 is an eye 12, and secured to each eye of each of said bolts is a connecting link 13, the opposite ends of said links being secured to a draw plate 14 by the nuts 15. Secured to said draw plate at 16 is one end of a coil spring 17, the opposite end of said spring being secured at 18 to the bracket 11. Secured at 19 to said draw plate 14 is one end of a connecting rod 20, the opposite end of said rod being pivotally secured at 21 to a pivoted plate 22, said plate being secured by the bracket 23 to the inside of the wall 1.

Secured to and extending from the plate 22 is a shifting handle 24, said handle protruding through a slot 25 which is formed in the wall 1.

In the operation of this improved locking device, when the sashes 3 and 4 are in their closed positions, the sockets 9 and 10 thereof are in alinement with their respective locking bolts 7 and 8, the locking bolts being normally held seated in their respective sockets by the contraction of the springs 17.

When it is desired to withdraw the locking bolts from their seated positions, the handle 24 is engaged and pushed toward the opposite end of the slot 25. This movement will cause the plate 22 to turn on its pivot, thereby exerting a pull on the connecting rod 20 and causing the draw plate 14 to act on the links 13, thereby withdrawing the bolts from their respective sockets.

The sashes are then unlocked ready to move to an open position. It is to be noted that the pressure of the spring 17 is normally tending to move the bolts 7 and 8 to their locking positions. Therefore, when the sashes are moved to their closed positions, in which the sockets thereof will be placed in alinement with their respective bolts, said bolts will immediately engage their respective sockets.

If it is desired to lock the upper and lower sashes 3 and 4 in opened positions, said sashes are moved to positions in which their respective sockets 26 and 27 will be in alinement with their respective locking bolts 7 and 8.

From the aforesaid description, it is readily seen that a locking device of an improved character relative to window sashes is provided, as the same cannot be tampered with from the outside, the locking bolts 7 and 8

rod 32, in dotted lines, connected to the pivots being embedded in the wood-work of their respective sashes, while the releasing mechanism, namely the pivoted plate 22, handle 24 and parts relating thereto are far out of reach of the intruder, even though a small opening is made in the window pane for the insertion of the arm of the intruder.

If desired a wearing surface can be provided for the locking ends of the bolts 7 and 8 as shown in Fig. 5, in which the sash 3^a has a metallic channel member 28 formed on one of the vertical strips thereof.

As shown in Fig. 6, if desired, a pair of locking devices A and B can be operated by one releasing mechanism C relative to a pair of windows D and E, in which the releasing mechanism can be arranged centrally of the windows, the pivoted plate 29 having pivotal connection with the connecting rods 30 and 31 of the locking devices A and B respectively.

For a further illustration as to how the connecting rods 30 and 31 are connected to the pivoted plate 29, attention is called to Fig. 2 which shows an extra connecting

rod 32 in opposite disposition to the connecting rod 20.

What I claim is:

1. A window frame, a pair of slidable sashes therefor, each bearing a socket, a pair of reciprocally mounted locking bolts mounted in said frame, each adapted to engage a respective socket, a draw link connected to each of said bolts, a spring for actuating said bolts mounted between said links, and a horizontally swinging lever connected to the opposite end of said links for drawing said bolts.

2. The combination of a window frame, a pair of slidably mounted sashes, each bearing a socket, and a locking device, said locking device comprising a pair of slidably mounted bolts arranged one above another and passing through said frame, a link secured to each of said bolts, said links at their opposite ends being secured to a draw plate, a horizontally swinging lever for operating said bolts, and a draw rod connected to said draw plate and said lever.

JOSEPH J. NEEDLE.
